(57) **CLAIM**

The ornamental design for a water pistol rack, as shown and described.

DESCRIPTION

FIG. 1 is an upper perspective view of the water pistol rack showing my design.

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof;

FIG. 8 is an upper perspective view thereof showing water pistols; and,

FIG. 9 is an upper perspective view thereof rotated about its base and showing water pistols.

The broken line showing of water pistols is for illustrative purposes only and forms no part of the claimed design.
